UNITED STATES PATENT OFFICE.

ISRAEL K. DIXON, OF JOHNSTOWN, PENNSYLVANIA.

SWITCH-OPERATING MECHANISM.

Application filed October 3, 1923. Serial No. 666,334.

To all whom it may concern:

Be it known that I, ISRAEL K. DIXON, a citizen of the United States, and resident of Johnstown, in the county of Cambria and

• State of Pennsylvania, have invented certain new and useful Improvements in Switch-Operating Mechanisms, of which the following is a specification.

This invention relates to switch operating mechanism and more particularly to the construction of the tongue operating mechanism for railway switches and the like.

10 One object of this invention is to provide a switch operating mechanism of improved construction and having novel means whereby the switch tongue is moved into and held in switching position on the switch body.

15 Another object is to provide a novel form of enclosing box for the switch operating mechanism which is adjustable bodily relative to the switch tongue to vary the throw of the tongue.

20 A further object is to provide a switch operating mechanism having the novel combination, construction and design of parts hereinafter described and illustrated in the accompanying drawings.

25 In the drawings, Figure 1 is a plan, showing a switch operating mechanism constructed and arranged and applied for use on a switch structure in accordance with my invention, the cover plate being removed from the operating mechanism for clearness.

30 Figure 2 is a sectional elevation taken on the line II—II of Figure 1.

Figure 3 is a sectional elevation taken at right angles to Figure 2 on the line III—III of Figure 1.

40 Figure 4 is a perspective view of one of the spring pressed rocker members.

Figure 5 is a perspective view of one of the toggle arms.

45 Figure 6 is a perspective view of the forward end of the reach rod extension.

Referring more particularly to the drawings, the numeral 2 designates the switch body of a tongue switch of a type adapted for use on street railways. The switch body is provided in its upper face with a longitudinal recess 3, in which the switch tongue 4 is pivotally mounted or positioned. The tongue 4 is pivoted at its heel on one end, in the recess 3, and the switch point on the opposite end of the tongue is arranged to swing sidewise from one side to the other

of the recess 3 against the sides 5 and 6 of the recess 3.

The switch operating mechanism forming my invention being adapted for use with any of the numerous known switch constructions, the switch is not fully illustrated or described in detail.

Secured on one side of the switch body 2 by means of the bolts 7, 7, is a rectangular hollow metal box or casing 8, having an open top side which is normally closed by a removable lid or cover plate 9.

Projecting downwardly from the lower side of the switch tongue 4, within the recess 11, to a point below the bottom of the recess 3 in the switch body 2, is an integral lug 12 having a transverse opening therein, in which one end of the reach rod section 13 is fastened by a nut 14 and lock nut 15. The opposite end of the rod 13 is screw threaded into an enlarged coupling 16 and a thimble or sleeve 17 is positioned on the rod 13 and forms a separator which serves to hold the rod 13 rigidly in position on the lug 12 when the nuts 14 and 15 are screwed tightly in place. The length of the thimble or sleeve 17 may be varied to suit the dimensions of various switches to which this switch operating mechanism is applicable.

50 A second box or casing 18 is mounted within the box or casing 8. The box 18 is provided with integral lugs 19 which project outwardly from the side faces thereof and are provided with screw threaded apertures adapted to receive threaded adjusting rods or bolts 20. The bolts or rods 20 are journaled in bearings 21 on the ends of the box 8 and are provided with hexagon portions 22 adapted to be engaged by a suitable tool when it is desired to rotate them. The box 18 is moved longitudinally of the bolts 20 and relative to the box 8 by rotation of the bolts 20, since the lugs 19 serve as nuts on the bolts.

55 The box 18 is provided with rocker arm supporting lugs 23 which project inwardly from the side faces of the box and are arranged in pairs. The lower lugs of each pair of lugs are integral with the bottom and sides of the box, while the upper lugs are integral with the sides of the box only. The lugs 23 terminate at their inner ends in spaced jaws or ears 24 which form bearings for the rocker arms.

60 The rocker arm 25 is mounted for horizontal rocking movement in each pair of

2
lugs 23. The arms 25 comprise a vertically disposed spindle portion 26 mounted between the ears or jaws 24 of the lugs 23, a forwardly projecting spring bearing portion 27 having a spring retaining projection 28 on their inner face, and a rearwardly projecting toggle arm bearing portion 29.

10 A coil spring 30 is mounted between the portions 27 of the arms 25 and tends to normally rock the arms about the vertical axis of their spindle portions 26, thus forcing the toggle arm bearing portions inwardly toward each other.

15 A pair of toggle arms 31 are arranged horizontally within the box 18, one of which is in engagement with each of the portions 9 of the arms 25. The toggle arms 31 terminate at their outer ends in vertically spaced jaws 32 and have a knife edge bearing portion 33 extending vertically between said jaws. The inner face of the portion 29 of each of the arms 25 is cut away to form a V-shaped bearing slot 34 adapted 20 to receive the knife edge bearing 33 of the toggle arms 31 and the upper and lower face of the portions 29 are cut away to form recesses 35 for the reception of the jaws 32.

25 The inner ends of the toggle arms 31 terminate in cylindrical bearing portions 36 adapted to fit within and engage against each other through an outwardly flaring perture 37 in the inner end or head 38 of a reach rod section 39. The reach rod section 39 extends through a stuffing box 40 in the end wall of the box 18 and is threaded into the opposite end of the coupling 16 from the reach rod 13 and is thereby movable with said reach rod.

30 The inner end or head 38 of the reach rod section 39 has vertically disposed tongues 41 and 42 on its upper and lower faces which extend into guideways 43 and 44, respectively, on the upper and lower walls of the box 18 so as to prevent sidewise movement of said extension.

35 The box 18 is of oil-tight structure and is adapted to be filled with oil so that all the working parts of the mechanism will be immersed in oil, thus facilitating their operation.

40 In the operation of switches equipped with the improved switch operating mechanism of this invention, the switch tongue 4 is moved manually, preferably with a switch iron, from one side to the other of the recess in the switch body. With the tongue positioned as shown in the drawings, the tongue 4 is adapted to be moved from right to left. When the tongue is moved from the position shown to the position at the opposite side of the recess 3, the reach rod will be also moved from right to left, thus forcing the toggle arms 31 inwardly and causing the arms 25 to rock

about their spindle axis and compress the spring 30. When the movement of the tongue is sufficient to force the toggle arms 31 past their dead center, the spring 30 will then exert its force to snap the tongue 70 through the remainder of its movement and also to prevent the accidental displacement of the tongue from its new position.

75 If for any reason it is desired to adjust the position of the reach rod relative to the switch tongue, it is only necessary to rotate the rods or bolts 20 and thus move the box 18 and its accompanying mechanism, including the reach rod, relative to the switch tongue. This construction permits the use 80 of a more rigid reach rod and eliminates the necessity for an adjustable joint in the rod.

I claim:—

85 1. The combination with a switch having a pivoted tongue, of a tongue operating mechanism comprising a box rigidly secured to said switch, a box mounted within said first named box and adjustable relative thereto, a reach rod connected to said tongue and extending into said second named box, and means within said second named box and connected to said reach rod for retaining said tongue in its different 90 positions.

95 2. The combination with a switch having a pivoted tongue, of a tongue operating mechanism comprising a box rigidly secured to said switch, a box mounted within 100 said first named box and adjustable relative thereto, a reach rod connected to said tongue and extending into said second named box, means for adjusting said second named box, and means within said second named box and connected to said reach rod for retaining said tongue in its different 105 positions.

110 3. The combination with a switch having a pivoted tongue, of a tongue operating mechanism comprising a box rigidly secured to said switch, an oil-tight box mounted within said first named box and adjustable relative thereto, means within 115 said first named box for adjusting the position of said second named box relative to said first named box, a reach rod connected to said tongue and extending into said second named box, and means within said second named box and connected to said reach rod for retaining said tongue in its different 120 positions.

125 4. The combination with a switch having a pivoted tongue, of a tongue operating mechanism comprising a box rigidly secured to said switch, an oil-tight box mounted within said first named box and adjustable relative thereto, a reach rod connected to 130 said tongue and extending into said second named box, and means within said second named box and connected to said reach rod

for retaining said tongue in its different positions.

5. The combination with a switch having a pivoted tongue, of a tongue operating mechanism comprising a box rigidly secured to said switch, a box mounted within said first named box and adjustable relative thereto, a reach rod connected to said tongue and extending into said second named box, 10 means for adjusting said second named box, and spring tensioned means within said second named box and connected to said reach rod for retaining said tongue in its different positions.

15 6. The combination with a switch having a pivoted tongue, of a tongue operating mechanism comprising a box rigidly secured to said switch, an oil-tight box mounted within said first named box and adjustable 20 relative thereto, a stuffing box mounted in the end wall of said second named box nearest said switch, a pair of horizontally disposed rocker arms mounted in said second named box for pivotal movement 25 about a vertical axis, a spring interposed between the forward ends of said arms, a pair of toggle arms engaged with the rear ends of said arms, and a reach rod passed through said stuffing box and connected to said toggle arms and to said switch tongue.

30 7. The combination with a switch having a pivoted tongue, of a tongue operating mechanism comprising a box rigidly secured to said switch, an oil-tight box mounted within said first named box and adjustable 35 relative thereto, a stuffing box mounted in the end wall of said second named box nearest said switch, a pair of horizontally disposed rocker arms mounted in said second

named box for pivotal movement about a 40 vertical axis, a spring interposed between the forward ends of said arms, a pair of toggle arms engaged with the rear ends of said arms, a reach rod connected to said switch tongue and projecting into said second named box, a head on the inner end of said reach rod having an opening into which the ends of said toggle arms are adapted to project, and cylindrical bearing 45 portions on the ends of said toggle arms 50 adapted to engage each other through said opening in said reach rod head.

8. The combination with a switch having a pivoted tongue, of a tongue operating mechanism comprising a box rigidly secured 55 to said switch, an oil-tight box mounted within said first named box and adjustable relative thereto, a stuffing box mounted in the end wall of said second named box nearest said switch, a pair of horizontally 60 disposed rocker arms mounted in said second named box for pivotal movement about a vertical axis, a spring interposed between the forward ends of said arms, a pair of 65 toggle arms engaged with the rear ends of said arms, a reach rod connected to said switch tongue and projecting into said second named box, a head on the inner end of said reach rod having an opening into which the ends of said toggle arms are 70 adapted to project, cylindrical bearing portions on the ends of said toggle arms adapted to engage each other through said opening in said reach rod head, and means for guiding said reach rod.

In testimony whereof, I have hereunto set my hand.

ISRAEL K. DIXON.
